(57) **CLAIM**

The ornamental design for a storage box, as shown and described.

DESCRIPTION

The file of this patent contains at least one drawing of the first embodiment executed in color. Copies of this patent with color drawing(s) will be provided by the Office upon request and payment of the necessary fee.

FIG. 1 is a front, top and right-side perspective view of a storage box showing a first embodiment of our new design; FIG. 2 is a front view thereof; with the rear view being a mirror image thereof;

FIG. 3 is a top view thereof;

FIG. 4 is a bottom view thereof;

FIG. 5 is a right-side view thereof; with the left-side view being a mirror image thereof;

FIG. 6 is a front, top and right-side perspective view of a storage box showing a second embodiment of our new design;

FIG. 7 is a front view thereof; with the rear view being a mirror image thereof;

FIG. 8 is a top view thereof;

FIG. 9 is a bottom view thereof; and,

FIG. 10 is a right-side view thereof; with the left-side view being a mirror image thereof.

The second embodiment sets forth Applicant's claimed design in gray scale.

The black background in the figures forms no part of the claimed design.
